(57) **CLAIM**

The ornamental design for a bottle warmer, as shown and described.

DESCRIPTION

FIG. 1 is a front, left and top perspective view of a bottle warmer showing my new design;

FIG. 2 is a front, right and top perspective view thereof;

FIG. 3 is a rear, left and bottom perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof;

FIG. 9 is a bottom plan view thereof; and,

FIG. 10 is an exploded perspective view thereof.

The dash-dash broken lines in the figures depict portions of the bottle warmer that form no part of the claimed design.
